UNITED STATES PATENT OFFICE.

HERMANN MOHR, OF MANNHEIM, BADEN, GERMANY.

APPARATUS FOR AUTOMATICALLY COUNTING AND REGISTERING RAILROAD-TRUCKS.

SPECIFICATION forming part of Letters Patent No. 379,800, dated March 20, 1888.

Application filed September 24, 1885. Serial No. 178,042. (No model.)

To all whom it may concern:

Be it known that I, HERMANN MOHR, a subject of the Grand Duke of Baden, residing at Mannheim, in the Grand Duchy of Baden, German Empire, have invented new and useful Improvements in Controlling Apparatus for Automatically Counting and Registering Railway Carriages, Trucks, and Similar Vehicles Passing Over It, of which the following is a specification.

My invention relates to improvements in apparatus for registering the number of railway-cars which pass over the track at a certain point in the line; and it consists, essentially, in arranging a portion of one of the rails constituting the track so that this portion is depressed when engaged by the wheels of the approaching car. Through its connection with a counter-lever, this yielding rail or rail-section actuates the index-hand of a counter connected with the counter-lever. In order that each car may be registered only once, the counter-lever is locked at each end of its vibration, and to unlock the counter-lever a second rail-section is centrally pivoted and is vibrated by the car-wheels as they engage with its respective arms, all of which is more fully pointed out in the following specification and claims, and illustrated in the accompanying drawings, in which—

Figure 1 represents a longitudinal vertical section in the plane $x x$, Figs. 2 and 3. Fig. 1^a shows sectional views of detail parts. Fig. 2 is a horizontal section of the apparatus in the plane $y y$, Fig. 1. Fig. 3 is a horizontal section of the same in the plane $z z$, Fig. 1. Fig. 4 is a vertical section in the plane $x' x'$, Figs. 2 and 3. Fig. 5 is a sectional side elevation of the counter and its connections, drawn to a larger scale than the preceding figures. Fig. 6 is a face view of the same. Fig. 7 is an end view of the counter.

Similar letters indicate corresponding parts.

In the drawings, the letter a designates an iron casing, which is situated partially beneath the road-bed and is open to allow the passage of the rail or rail-section a^3 , which is separate from the track-rails, but forms a continuous line therewith. This rail a^3 , which I shall hereinafter term the "yielding rail," is secured

to a bracket or frame, a^2 , that is secured to a shaft which has bearings in suitable sockets, $a' a'$, Fig. 2, extending from the bottom of the casing, so that when the car-wheels engage with this yielding rail the bracket or frame is turned about its hinges. 55

A is an upper casing supported upon tubular pillars $P P' P^2$, secured at their bases to the lower casing, a . In said casing A is located a lever, D , Figs. 1, 3, and 4, consisting of a straight arm, d , having on one of its ends a knife-head provided with two knife-edges, $d' d'$, Fig. 1. This knife-head is secured to the arm d at an inclination, so as to throw the knife-edges $d' d'$ out of a vertical line. The lower knife-edge, d' , Fig. 1, bears upon suitable supports, $d^* d^*$, rising from the bottom of the casing A , and the upper knife-edge, d' , is engaged by a link, J , Figs. 1 and 3, on the upper end of a rod, a^5 . The rod a^5 extends through the tubular pillar P^2 , and its lower end is connected with the free end a^4 , Figs. 1 and 4, of the bracket or frame a^2 . When the yielding rail a^3 is depressed by a passing car, the stress exerted upon the upper knife-edge, d' , causes the lever D to turn about the lower knife-edge, d' , as a fulcrum. The lever D , I shall hereinafter term the "counter-lever." The arm d of the counter-lever is of considerable length and carries an adjustable weight, d^3 . 70 The arc of vibration of this lever is limited at its upper end by an adjusting-screw, d^4 , the head of which comes into contact with a yoke-stop, d^5 , Figs. 1, 3, and 4, properly situated, and the lower end of the said screw is fixed by an adjusting-screw, d^6 , Fig. 1, impinging upon a block, p , Fig. 1, on the bottom of the casing. The arm d is also connected by a lever, E , Fig. 3, and gears, or by any other well-known means, with the post of an index-hand of a counter, A' , of the usual construction, so that the arm d actuates the counter by its vibrations. 80

The counter and its actuating mechanism will be hereinafter more fully described. 95

As thus constructed, the apparatus will register cars which pass over the yielding rail; but it is necessary that the apparatus should not repeatedly register a car which passes and repasses the yielding rail. For this purpose I 100

employ the following mechanism: A vertical lever, f' , Figs. 1, 1^a, 3, and 4, is pivoted at f'' to lugs on the casing, and carries near its central portion a spring-pressed latch-hook, d' , Fig. 5 1^a, especially, which engages and retains the arms d of lever D when said arm is in its highest position. A second latch-hook, d'' , pivoted to the upper end f'' , of the lever f' , locks the same when in its lowest position, so that a train can 10 pass and repass without being registered more than once. To release the counter-lever from the latch-hooks, I make use of unlocking-levers $D' D''$, that are connected by rods b^5 and b^6 to the respective ends of a rocking bar, b^4 , 15 which is centrally secured to a shaft, b , having bearings in the lower casing, a . This shaft b carries a rail-section, b^3 , Fig. 1, which lies just beyond the counting-lever, and is centrally secured to the said shaft, so that when 20 the rail-section, which I shall hereinafter term "the rocking rail" or rail-section, is engaged and released by the wheels it is turned about its fulcrum.

The unlocking-lever D' has a knife-edge fulcrum, h' , Fig. 1, which bears on supports h on the casing, and a knife-edge-and-link connection, J' , with the rod b^5 , precisely as those of lever D. The arm e of the lever D' extends toward the right hand of the casing, and is 25 provided with a weight, h^2 , Fig. 3, being limited in its swing by suitable stops. A vertical arm, e'' , Figs 1, 1^a, and 3, extending upward from the lever D' near its fulcrum, carries an adjusting-screw, e' , which engages with 30 one end of a bolt, f , that has bearings in lugs secured to the casing, and is provided with a pin, f'' , engaging a slot in the upper end, f'' , of the lever f' . When the car-wheels engage the end b^4 of the rocking rail b^3 , the unlocking-lever D' is moved by the screw e' , so as to 35 clear the hook d' from the lever D, which then falls to its lowest position, where it is engaged by the spring-pressed latch-hook d'' on the lever f' , so that if the car is backed over the yielding rail the lever D cannot be vibrated. 40 To release this latch-hook d'' , as the car-wheels leave the rocking rail, (when moving in the direction of arrow 1, Figs. 1 and 2,) I employ the unlocking-lever D'' , which is constructed 45 precisely like unlocking-lever D' , having a knife-edge fulcrum, h^3 , which bears on supports h^4 , and is connected to the rod b^6 by a link, j^2 . The long arm g of this lever carries a weight, h^5 , and its vertical arm g'' carries an adjusting-screw, g' , which engages the bolt f and throws 50 the same inward to release latch-hook d'' from the counter-lever D, when the vibrating rail is depressed.

The general operation of the apparatus is 55 as follows: When the car moves in the direction of arrow 1, the wheels depress the yielding rail a^3 , and the arm d is thrown upward, in which position it is locked by the latch-hook d' , and the car is registered. As the car-wheels depress the end b^4 of the rocking rail, 60 the hook d'' releases the lever D, and on its fall

it is locked by latch-hook d'' . When the wheels depress the end b^4 of the rocking rail, the latch-hook d'' releases the lever D, and the latter assumes its normal position. It is 70 evident that by thus locking the counter-lever D both in its highest and lowest positions the car is registered once only, no matter how many times it may act on the lever system. If the car strikes the rail-sections when moving in a direction opposite to arrow 1, it is not registered, because when the end b^4 of the rocking rail is depressed the lock d'' remains disengaged from the lever D, and as the wheels depress the end b^4 of the same the 75 hook d' locks the lever. When the wheels now strike the yielding rail, the lever D cannot vibrate. By properly adjusting the weights and the ratio of the lever-arms, the apparatus can be caused to register loaded cars only, unloaded cars not disturbing the lever system. 80

As shown in Figs. 5, 6, and 7, the lever E is secured at one end to the spindle r of the counter A' and connected at its other end to a crank-arm, r^2 , attached to a pivot, r' . The 90 lever A is attached at or near its center to the front end of the arm d of the counter-lever D. When said lever D is vibrated, the spindle r is turned to actuate the counter.

What I claim as new, and desire to secure 95 by Letters Patent, is—

1. The combination of the rail-section a^3 , a frame supporting the same, a lever, as D, connected with said frame, locks, as $d' d''$, for engaging the lever D, and a rail-section, b^3 , connected with said locks for releasing the lever D, substantially as shown and described. 100

2. The combination of the hinged frame, a rail-section supported by the same, a lever, as D, connected with the frame, locks, as $d' d''$, 105 for engaging the lever D, and a pivoted rocking rail-section, b^3 , connected with the locks, substantially as shown and described.

3. The combination of the detached rail-section a^3 , the hinged frame supporting the same, a counter, A', the counter-lever D, connected with said frame and said counter, the rocking rail-section b^3 , the arm f' , carrying latch-hooks engaging the lever D, and the connections between said arm and the said section b^3 , substantially as shown and described. 110

4. The combination of the detached rail-section a^3 , the hinged frame supporting the same, the weighted counter-lever D, having knife-edge bearings, the rod a^5 , connecting the counter-lever D with the supporting-frame, the rocking rail-section b^3 , centrally pivoted to a shaft, the rocking bar b^4 on said shaft, the unlocking-levers $D' D''$, connected by rods $b^5 b^6$ with the ends of the rock-bar, the arm f'' , the 115 latch-hooks $d' d''$ thereon, adapted to lock the lever D, and the bolt f , engaged by the levers D D' to vibrate the arm f' and release the lever D, substantially as and for the purpose set forth. 120

5. The combination of the detached rail-section a^3 , the hinged supporting-frame for the 125

same, a counter, A', the weighted counter-lever D, connected with the supporting-frame and said counter, means, as described, for adjusting its vibrations, the rocking rail-section 5 b³, the rock-bar b⁴, connected therewith, the unlocking-levers D' D², connected with the rock-bars, means for adjusting their vibrations, the arm f, carrying latch-hooks d⁵ d⁶, constructed to lock the lever D, and the bolt

f, engaged by the levers D D' to vibrate the 10 arm f', substantially as shown and described.

In testimony whereof I have signed my name to this specification in the presence of two subscribing witnesses.
